No. 867,670.

PATENTED OCT. 8, 1907.

A. M. NELSON.
ASH SIFTER.
APPLICATION FILED AUG. 21, 1905.

UNITED STATES PATENT OFFICE.

ANDREW M. NELSON, OF CHICAGO, ILLINOIS.

ASH-SIFTER.

No. 867,670.

Specification of Letters Patent.

Patented Oct. 8, 1907.

Application filed August 21, 1905. Serial No. 275,178.

To all whom it may concern:

Be it known that I, ANDREW M. NELSON, a citizen of the United States of America, and a resident of Chicago, Cook county, Illinois, have invented a certain new and useful Improvement in Ash-Sifters, of which the following is a specification.

My invention relates to sifting arrangements adapted more particularly to separating the unconsumed and but partially consumed coal from the ashes.

10 Generally stated, the object of my invention is the provision of an improved and highly efficient sifter, and one adapted more particularly for use in sifting ashes.

Special objects of my invention are the provision of 15 an improved construction and arrangement whereby the different elements of the sifter may have a more compact and efficient relative arrangement than heretofore; the provision of an improved construction and arrangement whereby the sifter will not tend to clog, 20 and may be easily operated, and whereby the same may be easily cleaned or repaired and renovated; and the provision of certain details and features of construction tending to increase the general efficiency and serviceability of a sifter of this particular character.

25 To the foregoing and other useful ends, my invention consists in matters hereinafter set forth and claimed.

In the accompanying drawings, Figure 1 is a longitudinal vertical section of a sifter embodying the principles of my invention, said section being taken on line 1—1 in Fig. 2. Fig. 2 is a vertical cross-section on line 2—2 in Fig. 1.

As thus illustrated, my improved sifter comprises a suitable box or body A having a drawer or receptacle B 30 for the unconsumed or but partially consumed coal, and another drawer or receptacle C for the ashes. As shown, the drawer B can be withdrawn from the lower front-portion of the box or body, while the drawer C can be withdrawn from the lower side-portion of the 40 box or body. Within the box, and at a point substantially over the meeting portions of the two drawers, a tilted or inclined screen D is arranged in the positions shown in Fig. 1,—that is, in such a position that any coal thrown upon its inclined upper surface will roll

45 down and fall into the drawer B, while the ashes will go through and fall into the drawer C. As an upward continuation of the said screen, a movable or swinging screen E is arranged in position with its lower end adjacent to the upper end of the screen D. The said 50 movable screen can be mounted to tilt about a horizontal axis e, and may have side boards or guards e' adapted to prevent anything thrown in the said movable screen from falling over the sides thereof. Another movable screen F is mounted to or tilt swing about a horizontal

axis f, both screens being connected by cords or other 55 flexible connections f' and e² with the swinging door or cover G. This door or cover is hinged to the top of the box at g, and when down, holds the two movable screens in the position shown in Fig. 1. A ledge or incline H is arranged in position to prevent the ashes, 60 when thrown into the sifter, from dropping directly into the drawer or receptacle B,—that is, for deflecting the ashes onto the screen D. When the cover or closure is opened, and swung into the position shown in dotted lines in Fig. 1, the two movable screens are thereby 65 lowered into the positions shown in dotted lines in said figure. In such relative positions, the screens permit the ashes to be deposited in the sifter through the opening covered by the swinging closure, and to fall first on the screen F, then onto the screen E; and at such time, 70 whatever passes through the screen F then falls upon the screen D. The ashes and finer portions pass through all the screens and fall into the receptacle C. Obviously, however, any coarser materials, such as the unburned coal, in falling on the screen D, then slide 75 downward and fall into the receptacle B. The cover G can then be swung into its closed position, and by so doing, the movable screens are restored to their normal positions. When this is done, any coal or coarse materials retained in the screen E will be dumped onto the 80 screen D, where they will then descend into the drawer or receptacle B. Thus the two upper screens are movable and are first drawn upward when the cover is closed, and then allowed to fall into their operative positions when the cover is opened; and with this arrangement, a certain amount of movable or shaking screen surface is provided for insuring a more effective screening and dumping of the ashes and unburned portions of the coal.

It will be seen that the two flexible connections f' 90 and e² may pass upwardly through an opening in the stationary top portions of the box, and thence across the top of the box to the point of attachment to the swinging closure.

What I claim as my invention is:

1. In an ash sifter, the combination with a receptacle, a cover therefor, a pair of screens adapted to be swung into operative position on the opening of said cover, whereby one of said screens assumes a downwardly extending position, permitting the passage of the coarser material onto the second screen, said second screen being in a substantially horizontal position and adapted to retain a coarse material on its surface, a third screen onto which said material is discharged on the closing of said cover, and a pair of removable receptacles arranged to receive 100 the fine material as it falls through the screen and the gross material as it falls off of the last screen.

2. In an ash sifter, the combination with a receptacle, a cover therefor, a pair of screens adapted to be swung into operative position on the opening of said cover, 110

whereby one of said screens assumes a downwardly extending position, permitting the passage of the coarser material onto the second screen, said second screen being in a substantially horizontal position and adapted to retain a coarse material on its surface, a third screen onto which said material is discharged on the closing of said cover, and a pair of removable receptacles arranged to receive the fine material as it falls through the screen and the gross material as it falls off of the last screen, and a

rigid deflector located in the upper part of said box 10 whereby the unsifted ashes are prevented from passing directly into said last-named receptacle.

ANDREW M. NELSON.
